UNITED STATES PATENT OFFICE

HORACE H. BURDETT, OF HOPEDALE, MASSACHUSETTS, ASSIGNOR TO DRAPER CORPORATION, OF HOPEDALE, MASSACHUSETTS, A CORPORATION OF MAINE
OUTGOING THREAD CONTROL FOR AUTOMATICALLY REPLENISHING LOOMS

Application filed April 4, 1929. Serial No. 352,445.

This invention relates to filling replenishing looms and is more particularly directed to the means for controlling the outgoing filling end or thread upon call for replenishment of filling.

In looms of this general type the outgoing filling end extends from the cloth selvage to the shuttle eye and thence to the filling carrier or bobbin in the shuttle. It has been found desirable in practice to part the old filling between the ends of the shuttle and preferably at a point adjacent the shuttle eye when the shuttle is properly boxed. In this connection also it is desirable to remove the filling end leading to the cloth selvage so that it will not be carried into the shed by the shuttle or the new filling and produce imperfect cloth, and various mechanisms have been devised for this purpose, among which is that shown and described in the patent to Alfred E. Stafford, No. 1,552,388, Sept. 1, 1925.

Some difficulty has been experienced in properly locating or positioning the thread to be parted adjacent the shuttle eye by reason of the fact that the length of filling between the shuttle eye and the cloth selvage is such as to cause the thread to drop out of the path of the cutting instrumentalities with the result that in some cases the outgoing thread fails to be parted and the objections hereinbefore stated are liable to occur.

One of the important features of the present invention consists in a thread positioner 35 for positioning or locating the outgoing thread for engagement by the thread parter following a call for replenishment of filling.

During the weaving operation the shuttle enters and leaves the replenishing box and another important feature of the invention consists in a thread positioner having a thread engaging portion which is normally under the influence of means for retaining the thread engaging portion of the positioner 45 retracted or outside of the shuttle box, thereby

avoiding contact of the shuttle therewith, and following a call for replenishment of filling, to move the positioner that its thread engaging portion may engage the thread within the shuttle box.

The invention and novel features thereof will best be made clear from the following description and accompanying drawings of one good form thereof.

In the drawings—

Fig. 1 is a perspective view of a replenishing shuttle box of a filling replenishing loom having the present invention associated therewith;

Fig. 2 is an enlarged sectional side elevation showing one form of thread parter, and the thread positioner in its inactive position during normal weaving operations;

Fig. 3 is a sectional side elevation showing the thread positioner as having performed its function and placed the thread in position for the action of the thread parter;

Fig. 4 is a section on the line 4—4 of Fig. 5;

Fig. 5 is a front elevation of a portion of the shuttle box having the present invention applied thereto;

Fig. 6 is an end view looking in the direction of the arrow of Fig. 5;

Fig. 7 is a section on the line 7—7 of Fig. 5, with a portion of the shuttle box broken away.

It has not been deemed necessary herein to illustrate and describe the replenishing mechanism whereby the filling in the shuttle is changed from time to time, because the 80 details of such mechanism form no essential part of the present invention and are now well understood in the art.

The lay 1, only a part of which is shown, may be of the usual construction, and at the 85 filling replenishing end thereof it is provided with the replenishing shuttle box 2 in which the shuttle 3 is located when replenishment of filling is to be effected, and as usual the shuttle 3 has the side delivery eye at its lead- 90

ing or right hand end of Fig. 1, from which the filling *a* is drawn during the weaving operation.

The thread parter for parting the outgoing filling end may be of usual construction, since the details thereof are unimportant in connection with the present invention, but as herein illustrated the thread parter consists of the two jaws or cutter members 4 and 5, one at least of which is movable to cause the parter when open to part the thread when the members are closed. In the illustrated form of the parter there is a fixed member 4 and a movable member 5 which is pivotally connected with the fixed member at 6 and has a pin 7 extending therefrom at its front end portion, such pin being utilized first to open the parter and then later to cause it to part the thread.

20 The thread parter is shown as mounted upon a carrier or slide 8 which upon call for replenishment of filling is moved rearwardly under the dictates of an arm 9 having a slot 10 which engages a pin 11 extended from 25 the carrier or slide.

Upon call for replenishment of filling, the arm 9 moves the slide 8 rearwardly and the trip 12 opens the parter into the general position indicated in Fig. 2. When the parter 30 is in its rearward parting position and the thread is engaged between the members thereof the parter members are closed in an appropriate manner to part the thread. In the present instance the parters are closed by 35 the closing member 13 which is connected to the transerrer so that on downward movement of the transerrer the parter will be closed to part the thread. The details thus far described may be of the same general 40 construction and operation as shown and more fully described in the Stafford patent above mentioned.

As usual in filling replenishing looms where the outgoing filling is to be parted between the ends of the shuttle or adjacent the shuttle eye, the front box plate 14 is provided with an opening 15 through which the parter may pass to engage and cut the thread, and as usual the shuttle 2 is provided with 50 a longitudinal recess 16 in which the thread *a* rests when the shuttle is in the replenishing box. It may be desirable to enlarge the opening 16 in the side of the shuttle adjacent the side delivery eye, but the character of 55 opening 16 as shown is sufficient in size to accommodate the thread and operation of the parter and positioner, as will later appear.

In accordance with the present invention 60 the thread positioner has a thread engaging portion which is normally retracted from the shuttle box and is caused to enter the shuttle box when the shuttle is in position for replenishment, and engage and position 65 the thread for the parting operation.

The thread positioner, in accordance with the present invention, is mounted on the shuttle box and preferably supported by the front wall thereof adjacent the opening in the wall through which the parter may extend when it is positioned to part the filling.

The front wall or box plate of the shuttle box has an enlarged portion 17 which forms a convenient means for the thread positioner mounting, but any suitable supporting structure on the shuttle box or front wall thereof may be employed.

As shown in the present instance of the invention the shuttle positioner 18 is provided with a thread engaging portion 19 and is mounted for rotative movement through a train of mechanism comprising the shaft 20 of the positioner having teeth 21 on a portion thereof which are engaged with a pinion 22 mounted for rotative movement upon a supporting wall 23 of the front box plate.

The mounting for the pinion 22 may be variously contrived, but as shown in the present instance the head end portion 24 of the pinion mounting extends through the pinion 22 and is threaded at 25 into the end portion of the elongated gear 26, the construction being such that should the elongated gear 26 be rotated it will act through the pinion 22 and the teeth 21 of the positioner, to cause a rotative movement of the latter.

Mounted above the elongated gear 26 is a plunger 27 having a series of teeth 28 which are engaged with the teeth of the elongated pinion 26, the construction being such that upon longitudinal movement of the plunger 27 the elongated pinion 26 will be actuated and transmit turning movement to the thread positioner.

The plunger 27 as shown is mounted for longitudinal movement in an opening 29 formed in the front box plate of the shuttle box and is under the normal influence of a spring 30 tending to move the plunger in its outward position, as indicated in Fig. 7, and a stop 31 on the plunger serves to limit its outward position.

From the construction thus far described it will be apparent that under the normal action of the spring 30 the plunger will cause the thread positioner to assume the position indicated in Fig. 7 with the thread engaging portion of the thread positioner retracted from the shuttle box, a position the thread positioner occupies during normal weaving between replenishing operations.

Extending rearwardly from the parter carrier or slide 8 is a bunter 32 the head portion 33 of which is adapted to engage with the outwardly projecting end of the plunger 27 when the bunter, on call for replenishment of filling, has been moved rearwardly with the parter carrier to position the parter for its thread cutting operation as the lay moves frontwardly. The shuttle to be replenished

will, at this time, be in the replenishing shuttle box and the action of the bunter upon the plunger serves to move the thread positioner to place its thread engaging portion or hook 19 within the shuttle box to engage and position the thread.

After replenishment when the lay moves towards its back position, the end of the plunger 27 will be freed from the bunter 32 with the result that the normally acting spring 30 will move the plunger to its outer position and perforce move the thread positioner to withdraw the thread engaging portion thereof from the shuttle box so that during subsequent weaving it will not be engaged by the shuttle as the lay enters and leaves the box.

It will be noted from the construction shown and described as one good practical form of the present invention that the thread positioner is located adjacent the opening 15 in the front box plate which is in proximity to the shuttle eye when the shuttle is in the replenishing box. The effect of this is that the thread engaging portion of the thread positioner will hold the thread adjacent the shuttle eye for the action of the thread parter.

The thread positioner, shown as one good practical form of the invention, is mounted for rotative movement, and its thread engaging portion or hook 19 passes into the shuttle box under the dictates of the bunter and lifts the thread, which is usually liable to fall below the line of action of the parter. As the thread positioner is turned as stated its thread-engaging portion or hook 19 will carry the thread frontwardly to some extent, as indicated in Fig. 3, wherein it will be noted that the thread *a* has been carried between the two members of the thread parter. Thus, not only does the thread positioner engage and position the thread in the shuttle box, but serves to move the thread frontwardly to a degree to insure that it be placed within the parting action of the parter.

The parter as herein shown and described is, as stated, substantially of the same general character as that shown and described in the Stafford patent, but, so far as the present invention is concerned, the parter may be variously contrived and preferably will have associated therewith a clamping member 34 so that when the thread has been parted and the end leading to the shuttle eye has been freed, the end leading to the cloth selvage will be held by the parter clamp and consequently be moved frontwardly about the cloth selvage as a center, as the parter moves frontwardly to its normal position.

To enable the end of the thread *a* leading to the cloth selvage to be thus swung frontwardly out of the shuttle box, the front box plate is provided with an inclined groove 35 leading to the top of the shuttle box as at 36, so that as the end of the thread leading to the

cloth selvage is moved frontwardly by the clamp, the thread end will ride through the inclined slot or opening 35 and be withdrawn frontwardly over the top of the shuttle box.

As is well understood the ends of the filling or threads to be transferred to the shuttle during replenishment are secured at a fixed point and when the fresh filling is placed in the shuttle and the latter is picked, this filling end is liable to be caught by some part in the shuttle box and eventually be carried into the shed. To prevent this objectionable condition the front plate of the shuttle box is provided with an arm 37 which extends frontwardly and has a downwardly extending hook end portion 38 so that as the new filling ends rest upon the frontwardly extending portion 37 of the arm and drop slightly as the lay goes back, they will be engaged by the hooked end portion 38 of the arm and retained from the operating parts and from being carried into the shed.

The arm 37 may be secured to the enlargement 17 of the front box plate by a screw or other fastening means 39.

The primary purpose of the thread positioner, as hereinbefore stated, is to position the thread adjacent the shuttle eye for the action of the thread parter, and to insure that the thread be parted on replenishment of filling. Should the thread engaging portion of the thread positioner, however, be sharpened, it would serve to part the filling, and in such case the parted end leading to the cloth selvage would be withdrawn frontwardly by the thread clamp as the lay goes back.

The train of mechanism described for normally holding the thread engaging portion of the thread parter retracted from the shuttle box during weaving and between filling replenishment operations, and for projecting the filling engaging portion of the positioner into the shuttle box when filling is to be replenished, forms a good practical construction, but, obviously, the details of such mechanism may be varied within the ordinary skill of the weaving artisan.

What is claimed is:

1. In a filling replenishing loom, the combination of a thread parter to act upon and part the outgoing thread between the ends of a shuttle when in the replenishing shuttle box, a thread positioner mounted on the shuttle box and having a thread engaging portion, and means rendered effective on call for replenishment of filling to move the thread engaging portion of the positioner into the shuttle box to engage and position the thread for the action of the parter.

2. In a filling replenishing loom, the construction of a thread parter to act upon and part the outgoing thread between the ends of a shuttle when in the replenishing shuttle box, a thread positioner mounted for move-

ment on the shuttle box and having a thread engaging portion normally outside of the shuttle box, and means rendered effective on call for replenishment of filling to project 5 the thread engaging portion of the positioner into the shuttle box to engage and position the thread for the action of the parter.

3. In a filling replenishing loom, the combination of a thread parter mounted to act 10 upon and part the outgoing thread between the ends of the shuttle when in the shuttle box, a thread positioner mounted on the shuttle box and having a thread engaging portion, and means rendered effective on call for 15 replenishment of filling to move the thread engaging portion of the positioner into the shuttle box as the lay moves frontwardly to position the outgoing thread for the action of the parter.

20 4. In a filling replenishing loom, the combination of a thread parter to act upon and part the outgoing thread adjacent the shuttle eye, a thread positioner mounted on the shuttle box and having a thread engaging 25 portion adjacent the shuttle eye when the shuttle is boxed, and means rendered effective to move the shuttle positioner as the lay beats up after a call for replenishment of filling to move the thread engaging portion 30 of the thread positioner into the shuttle box to engage and position the thread for the action of the parter.

5. In a filling replenishing loom, the combination of a thread parter to act upon and 35 part the outgoing thread adjacent the shuttle eye, a thread positioner mounted on the shuttle box for movement relative thereto and having a thread engaging portion adjacent the shuttle eye when the shuttle is boxed, 40 means rendered effective to move the thread positioner on the shuttle box as the lay beats up after a call for replenishment of filling to project the thread engaging portion of the thread positioner into the shuttle box to 45 engage and position the thread for the action of the parter, and means for withdrawing the thread engaging portion of the positioner from the shuttle box after the thread has been parted.

50 6. In a filling replenishing loom, the combination of the replenishing shuttle box having a front box plate provided with an opening adjacent the eye of a boxed shuttle, a thread parter to act upon and part the outgoing thread adjacent the shuttle eye, a thread positioner having a thread engaging portion adjacent the eye of a boxed shuttle and normally outside of the shuttle box during weaving, and means rendered operative 55 on call for replenishment of filling for actuating the thread positioner to move the thread engaging portion of the positioner into the shuttle box to position the thread for the action of the parter.

65 7. In a filling replenishing loom, the com-

bination of the replenishing shuttle box having a front box plate provided with an opening adjacent the eye of a boxed shuttle, a thread parter to act upon and part the outgoing thread adjacent the shuttle eye, a thread positioner having a thread engaging portion adjacent the eye of a boxed shuttle and normally outside of the shuttle box, means for actuating the thread positioner to move the thread engaging portion of the positioner into the shuttle box to position the thread for the action of the parter, and means for withdrawing the thread engaging portion of the positioner from the shuttle box to prevent contact of the shuttle therewith 70 75 80

8. In a filling replenishing loom, the combination of the replenishing shuttle box having a front box plate provided with an opening adjacent the eye of a boxed shuttle, a thread parter to act upon and part the outgoing thread adjacent the shuttle eye, a thread positioner mounted on the shuttle box and having a thread engaging portion normally outside of the shuttle box adjacent the eye 90 of a boxed shuttle, and means for actuating the thread positioner to move the thread engaging portion of the positioner into the shuttle box to position the thread for the action of the parter. 95

9. In a filling replenishing loom, the combination of the replenishing shuttle box having an opening adjacent the eye of a boxed shuttle, a thread parter adapted to enter said opening and part the outgoing thread after 100 call for replenishment of filling, a thread positioner mounted on the front wall of the shuttle box and having a thread engaging portion, means normally acting to maintain the thread engaging portion outside the shuttle box to prevent contact by the shuttle, and means acting after call for replenishment for moving the thread engaging portion of the positioner into the shuttle box to position the thread for the action of the thread parter. 105 110

10. In a filling replenishing loom, the combination of a thread parter to part the outgoing thread adjacent the eye of a shuttle in the replenishing shuttle box, a thread positioner having a thread engaging portion normally held outside of the shuttle box during weaving, and means rendered effective upon call for replenishment of filling to move the thread engaging portion into the shuttle box 115 and in a plane to position the outgoing thread for the action of the parter. 120

11. In a filling replenishing loom, the combination of a thread parter to part the outgoing thread adjacent the eye of a shuttle in the replenishing shuttle box, a thread positioner having a thread engaging portion, means normally effective for holding the thread engaging portion out of the shuttle box and the path of the shuttle between re- 125 130

plenishing operations, and means rendered effective upon call for replenishment of filling to move the thread engaging portion into the shuttle box and in a plane to position the outgoing thread for the action of the parter.

12. In a filling replenishing loom, the combination of the replenishing shuttle box having a front box plate provided with an opening, a thread engaging member mounted on the shuttle box and having a part to enter said opening and engage the outgoing thread, means normally effective upon the engaging member to hold said part out of the path of the shuttle, and means effective upon call for replenishment of filling to actuate the thread engaging member to cause said part thereof to enter the shuttle box and engage the outgoing thread.

13. In a filling replenishing loom, the combination of the replenishing shuttle box having a front box plate provided with an opening, a thread engaging member mounted on the shuttle box and having a part of hook formation to enter said opening and engage the outgoing thread, means normally effective upon the engaging member to hold said part out of the path of the shuttle, and means effective upon call for replenishment of filling to actuate the thread engaging member to cause said part thereof to enter the shuttle box and engage the outgoing thread.

14. In a filling replenishing loom, the combination of the replenishing shuttle box having an opening in its front wall, a thread engaging member mounted for rotative movement on the shuttle box and having a thread engaging hook adapted to enter the opening in the front wall of the shuttle box, means normally tending to retain the thread engaging hook from entering the shuttle box, and means positioned to turn the thread engaging member when filling is to be replenished and project the thread engaging hook into the shuttle box to engage the thread.

15. In a filling replenishing loom, the combination of the lay having a replenishing shuttle box, a thread parter to part the outgoing thread at a point between the ends of the boxed shuttle, a thread positioner mounted on the lay and having a thread engaging portion normally outside of the shuttle box, and means rendered effective on call for replenishment of filling to operate the thread positioner and cause the thread engaging portion thereof to engage the outgoing thread in the shuttle box and withdraw it from the shuttle box into a position for the action of the thread parter.

16. In a filling replenishing loom, the combination of the replenishing shuttle box having an opening in its front wall, a thread engaging member mounted for rotative movement on the shuttle box and having a thread engaging hook adapted to enter the opening in the front wall of the shuttle box, means

normally tending to retain the thread engaging hook out of the shuttle box, means positioned to turn the thread engaging member when filling is to be replenished and project the thread engaging hook into the shuttle box 70 to engage the thread, and a thread clamp for withdrawing the end of the thread leading to the cloth selvage from the shuttle box.

In testimony whereof, I have signed my name to this specification.

HORACE H. BURDETT.
